US00D874520S

(12) **United States Design Patent** (10) Patent No.: **US D874,520 S**
(45) Date of Patent: ** Feb. 4, 2020

(54) **DISPLAY SCREEN OR PORTION THEREOF WITH ICON**

(71) Applicant: **Samsung Electronics Co., Ltd.**, Suwon-si (KR)

(72) Inventors: **Giulio Americo Tolesano Pascoli**, Sunnyvale, CA (US); **Philip Park**, Mountain View, CA (US)

(73) Assignee: **SAMSUNG ELECTRONICS CO., LTD.**, Gyeonggi-Do (KR)

(**) Term: **15 Years**

(21) Appl. No.: **29/643,000**

(22) Filed: **Apr. 3, 2018**

(51) LOC (12) Cl. **14-04**

(52) U.S. Cl.

USPC **D14/495**

CLAIM

The ornamental design for display screen or portion thereof with icon, as shown and described.

DESCRIPTION

The FIGURE is a front view of a display screen or portion thereof with icon showing our new design.

The outermost broken lines illustrate an electronic device, which is the environment of the design, and form no part of the claim. The remaining broken lines illustrate a display screen or portion thereof and portions of the graphical user interface, and form no part of the claimed design.

1 Claim, 1 Drawing Sheet
